Primary Examiner — Mark Goodwin(74) *Attorney, Agent, or Firm* — Workman Nydegger(57) **CLAIM**

The ornamental design for an attachment device, as shown and described.

DESCRIPTION

FIG. 1 is a front perspective view of the attachment device; FIG. 2 is a rear perspective view of the attachment device; FIG. 3 is a front view of the attachment device; FIG. 4 is a top view of the attachment device; FIG. 5 is a left side view of the attachment device, with the right side view being a mirror image thereof; FIG. 6 is a rear view of the attachment device; and, FIG. 7 is a bottom view of the attachment device. The broken lines shown in the figures are for illustrative purposes only and form no part of the claimed design.
